UNITED STATES PATENT OFFICE.

FRANK C. YOUNG, OF NEW HAVEN, CONNECTICUT.

DEVICE FOR TEACHING PENMANSHIP.

SPECIFICATION forming part of Letters Patent No. 783,497, dated February 28, 1905.

Application filed February 24, 1904. Serial No. 195,106.

To all whom it may concern:

Be it known that I, FRANK C. YOUNG, a citizen of the United States of America, residing at New Haven, in the county of New Haven 5 and State of Connecticut, have invented a certain new and useful Improvement in Devices for Teaching Penmanship; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My invention relates to improvements in a device for teaching penmanship; and the objects of my invention are, first, to give the fingers and thumb of the pen-holding hand such support that they will be held in the correct 20 position for both the free-hand and the muscular movements while writing; second, to give proper support to the pen-holder while the hand is held in the correct position for using the free-hand and muscular movements in 25 writing; third, to so hold the fingers and thumb of the pen-holding hand that the writer will be unable to use the finger movement while writing.

I attain these objects by the mechanism illustrated in the accompanying drawings, in which—

Figure 1 represents a view of the mechanism in its most complete form; Fig. 2, a view of the palm of the hand, showing the fingers and thumb held by the device in their correct position, with the penholder in place. Fig. 3 represents a view of the hand with the device in position holding the fingers and thumb in the correct position, with the penholder in 40 place.

Referring to Figs. 1, 2, and 3, A designates a loop formed by bending the ends of a piece of wire into the required shape and bringing them together at B. From B the wire is 45 twisted to form a shank BC, and from C one end is continued, forming section E, on which the ring H slides, the socket D, and the thumb-rest F and ending at G, this end being supported on the shank BC. On E a wire ring I, 50 H is placed, fastened to E by small ring I.

This small ring I is so constructed that it may be slipped around the socket D and H removed at any time. The small ring I permits H to slide on E. From C the other end of the wire is bent into the shapes J, K, L, M, 55 N, and O. This end of the wire meets the rest BC at P. The wire is turned around the rest BC at P and continued to Q, (its end,) forming the recess R, the bends J and M forming arches to pass over the third finger, 60 and the bend O forming an arch over the forefinger.

The operation of the device is as follows: The thumb of the pen-holding hand is inserted through loop A, the end of thumb resting on 65 rest F, holding the penholder with the first and middle finger in the correct way. The first finger is placed under the arch O. The middle finger is placed over N and through the socket D. The third finger is placed under the 70 wire forming arches M and J, and the little finger over the bends L and K. The series of bends hold the fingers so that the nails of the little and third fingers may touch the desk, and the penholder be held with the other two 75 fingers and thumb, as shown by Fig. 3.

The lower shank of the penholder is placed in the ring H and the upper shank in the spring-recess R, being pressed into said recess until sufficient support is given. The ring H 80 is then adjusted on E to suit the fingers of the writer and the device is ready for use.

I claim wire as the best material for the construction of my mechanism, but do not desire to limit myself to this material for its 85 construction, as it may be made of different material to better advantage.

This device is simple, durable, and inexpensive.

Having described my invention, what I claim 90 as new, and desire to secure by Letters Patent, is—

1. A device for teaching penmanship consisting of a loop for the thumb, a shank at the inner end of the loop, a socket for the second 95 or middle finger, a rest for the end of the thumb, arches to extend over the first and third fingers, and a rest projecting beyond the little finger, and all formed from a single piece of wire, substantially as described. 100

2. A device for teaching penmanship consisting of a loop for the thumb, a shank at the inner end of the loop, a socket for the second, or middle finger, a rest for the end of the thumb, arches to extend over the first and third fingers, a rest projecting beyond the little finger, and a recess to the left of the forefinger-arch and between the thumb-loop and thumb-rest to receive a penholder or pencil, substantially as described.

3. A device for teaching penmanship con-

sisting of a loop for the thumb, a shank at the inner end of the loop, a socket for the second or middle finger, a rest for the end of the thumb, arches to extend over the first and third fingers, a rest projecting beyond the little finger, and a movable ring between said socket and shank, substantially as described. 15
